CARTON AND BLANK THEREFOR

Carroll K. Lavere, Lancaster, Ohio, assignor to
 Anchor Hocking Glass Corporation, Lancaster,
 Ohio, a corporation of Delaware

Application March 14, 1938, Serial No. 195,745

9 Claims. (Cl. 229—37)

This invention relates to cartons for receiving pieces of hollow ware such as a bowl of glass or other hollow article of a frangible material.

An object of the invention is to provide an improved carton whereby it can be manufactured at small cost and yet provide ample protection against injury or destruction of ware in handling or in transportation.

Another object of the invention is an improved construction of carton whereby packing material such for example as excelsior or sawdust is rendered unnecessary. Other objects will appear from the disclosure herein.

The invention is embodied in the construction herein shown and described, the feature of novelty being pointed out in the claim.

In the accompanying drawing illustrating an example according to the invention,—

Figure 1 is a plan view of the prepared blank with which the carton is formed.

Fig. 2 is a plan view illustrating a portion of the interior of the carton containing a bowl.

Fig. 3 is a side view with parts opened illustrating the manner in which the bowl engaging tongues are applied.

Fig. 4 is a perspective view, on a smaller scale illustrating how the carton is sealed after the outer covering panels are closed.

Referring first to Fig. 1 the blank is formed preferably from a strip of double faced corrugated paper board or any other suitable material such as required or permitted by the postal authorities or transporting companies, the said strip being of rectangular oblong form and die cut to form the members substantially as shown. The full lines within the boundaries of the blank of the view said Fig. 1 illustrates die cut lines and the broken lines indicate scoring or bending lines. Where the paper is thick these latter lines should be depressed.

The bending or hinging lines referred to define twelve panels of nearly equal form and dimensions there being three in each of the vertical or transverse rows, the plain rows alternating with the rows containing the tongues or bowl-engaging members indicated.

The two panels 5 and 7 and the two panels 6 and 8 respectively are substantially identical in that they have cut therein the pairs of tongues 5^a and 7^a and the pairs 6^a and 8^a respectively for engaging respectively the interior of the wall of the bowl (designated 14) near the top thereof and the exterior of the wall of the bowl near its bottom. The said tongues are to be bent on their

hinging lines preparatory to cause their engagement with the ware.

The panels 9, 10, 11 and 12 are destined to form the vertical walls of the carton, and when, in the process of forming the carton, the blank is bent or closed on the transverse lines a—a, b—b and c—c until the outer extremities of the panels 9 and 12 meet the said panels 9 to 12 inclusive constitute such vertical walls of the carton and are held in said position by an adhesive strip 13 of paper or cloth applied to the meeting margins only of the panels as indicated in Fig. 4.

When in the form brought by the operation described in the next preceding paragraphs the panels 6 and 8 with their tongues 6^a and 8^a are suitably projected on their hinging lines and the said panels 6 and 8 are elevated to horizontal position as shown in Fig. 3 their said tongues 6^a and 8^a engage the exterior wall of the bowl near its bottom. After this the panels 5 and 7 with their tongues 5^a and 7^a are projected inward on their bending lines and the panels 5 and 7 turned downward on their hinging lines to cause said tongues to engage the interior wall of the bowl near its top.

When the panels 5 and 7 are closed the notches 5^b and 7^b in the free edges thereof coincide and form a convenient hole for the insertion of a finger of the hand to lift either of said panels.

The panels 17 and 18 when bent upward to horizontal position on their hinging lines form the two halves of the closing bottom of the carton; and likewise when the panels 15 and 16 are bent downward to horizontal position on their hinging lines these form the two halves of the top closure of the carton. The meeting lines of the said closed panels 17 and 18 and 15 and 16 respectively lie parallel to each other in the same vertical plane so that upon the application of one or more strips 19 of adhesive paper to the meeting margins as indicated in Fig. 4 serve to seal and hold said closing panels together and in place to form the carton, ready for delivery.

It will be noted that the panels 10 and 12 between the panels containing the ware engaging tongues are shown as being a little narrower than the longitudinally contiguous panels 9 and 11, and that this difference promotes parallelism of the closing panels 15 and 17 and 16 and 18, with the tongue panels when the said closing panels are turned to lie over the tongued panels.

Because the tongued panels 5 and 6 and 7 and 8 when turned to position to engage their tongues with the ware, fit rather closely between the side walls, 9 and 11, said panels serve to brace all the

side walls against collapse after the members are secured together as in Fig. 4.

From the construction shown and described, it will be observed that the ware contained by the 5 carton is held by the panels and tongues thereof from movement in any direction in relation to the carton; and because, as shown, the ware is held spaced from the main or lateral walls of the carton especially by the tongues engaging the ware 10 externally (see Fig. 3), there is little or no danger of breakage in the ordinary handling and transportation of the package.

The material, form, size and number of the 15 parts can be varied without departing from the gist of the invention as claimed.

What I claim is:

1. A carton for containing a piece of hollow ware formed of a blank including a row of panels 20 bent on bending lines to form the sides of the carton, panels bendably connected with opposed edges of alternate panels in the said row of wall forming panels, said last named panels containing 25 tongues bendable therefrom to engage the interior and exterior sides of the wall of the ware between its top and bottom.

2. A carton for containing a piece of hollow ware formed of a blank including a row of panels 30 bent on bending lines to form the sides of the carton, panels bendably connected with opposed edges 35 of alternate panels in the said row of wall forming panels, said last named panels containing tongues bendable therefrom to engage the interior and exterior sides of the wall of the ware between its top and bottom, said tongues in the upper panel 40 of the carton being spaced from each other differently from the spacing of those in the lower panel.

3. A carton for containing a piece of hollow ware formed of a blank including a row of panels 45 bent on bending lines to form the sides of the carton, panels bendably connected with opposed edges of alternate panels in the said row of wall forming panels, said last named panels containing 50 tongues bendable therefrom to engage the interior and exterior sides of the wall of the ware between its top and bottom and panels bendably connected with other alternate panels in said sides forming row constituting covers for said tongued panels.

4. A carton for containing a piece of hollow ware formed of a sheet of suitable material including longitudinally three rows of substantially equal rectangular panels and provided with 55 cuts and bending lines dividing the blank into four transverse portions of three panels each, the longitudinally interior panels of said blank forming side walls of the carton and the external panels of the second and fourth of said transverse rows constituting top and bottom wall portions of 60 the carton and provided with bendable tongues for engaging internally and externally the wall of the hollow ware between its top and bottom.

5. A carton for containing a piece of hollow ware formed of a sheet of suitable material in-

cluding longitudinally three rows of substantially equal rectangular panels each of said panels being of substantially a length twice that of its width and provided with suitable cuts and bending lines dividing the panels into four groups of transverse bendable portions of three panels each, the longitudinally interior panels of said blank forming the side walls of the carton and the external panels of the second and fourth of said transverse rows forming top and bottom wall portions 10 of the carton, said last named wall portions provided with bendable tongues for engaging the wall of the hollow ware internally and externally between its top and bottom. 5

6. A carton for containing a piece of hollow 15 ware formed of a sheet of suitable material including longitudinally three rows of substantially equal rectangular panels each of said panels being of substantially a length twice that of its width and provided with suitable cuts and bending lines 20 dividing the panels into four groups of transverse bendable portions of three panels each, the longitudinally interior panels of said blank forming the side walls of the carton and the external panels of the second and fourth of said transverse rows 25 forming top and bottom wall portions of the carton, said last named wall portions provided with bendable tongues for engaging the wall of the hollow ware internally and externally between its top and bottom and finger-receiving notches in 30 said last named top wall portions for manipulating them.

7. As an article of manufacture a blank for forming a carton to receive a piece of hollow ware, 35 said blank including a row of panels, panels bendably connected with opposed edges of alternate panels in said row of panels, said last named panels containing tongues bendable therefrom to engage the interior and exterior sides of the wall 40 of the ware between its top and bottom. 40

8. As an article of manufacture a blank for forming a carton to receive a piece of hollow ware, 45 said blank including a row of panels, panels bendably connected with opposed edges of alternate panels in said row of panels, said last named panels containing 50 tongues bendable therefrom to engage the interior and exterior sides of the wall of the ware between its top and bottom, and bendable panels connected with other alternate panels in said side-forming row constituting covers for 55 said tongued panels.

9. As an article of manufacture a blank for a hollow ware container including a sheet of suitable material having bending lines dividing it into a row of four carton side walls, top and bottom 55 panels bendably connected with alternate of said side wall forming panels, one of said last named panels provided with bendable tongues to engage the interior surface of the wall of the ware between its top and bottom and the other of said panels provided with bendable tongues to engage the exterior surface of the ware between the top 60 and bottom thereof.

CARROLL K. LAVERE.
